UNITED STATES PATENT OFFICE.

OTIS SASSER, OF CLOVIS, NEW MEXICO.

CARBONATED-WATER-CUT-OFF VALVE FOR SODA FOUNTAINS.

Application filed December 2, 1926. Serial No. 152,200.

This invention relates to soda fountains and more particularly to valve mechanisms by which the flow of carbonated water is controlled. It is well known in dispensing 5 soda water that the water when first drawn into the glass must not disturb the syrup therein and that thereafter it is preferable to discharge a fine stream under full pressure that will pass through the entire liquid 10 contents of the glass and thoroughly incorporate the syrup at the bottom of the glass with the carbonated water.

It is an object of the present invention therefore to provide a soda water dispensing 15 device including inner and outer conduits and leak-proof valve mechanisms by which the fluid may be allowed to pass through either of these conduits and by which both conduits will be automatically 20 closed when not desired for use.

It is a further object of the present invention to provide a valve mechanism for controlling the flow of liquid through the conduits; the valve mechanism being disposed adjacent the bottom of the fountain 25 rather than in a faucet and being operated by the foot, whereby both hands of the operator may be left free for other duties.

A further object of the invention resides 30 in the provision of a valve mechanism comprising relatively few parts which is free from leather washers and the like, and which is therefore strong and durable in operation.

Other objects and advantages of the invention will be apparent from the following 35 description taken in connection with the accompanying drawing; in which

Figure 1 is a fragmentary rear view of a soda fountain.

Figure 2 is an end elevation thereof.

Figure 3 is a fragmentary longitudinal section taken on line 3—3 of Figure 2.

Figure 4 is a horizontal section taken on line 4—4 of Figure 3; and

Figures 5 and 6 are fragmentary longitudinal sections showing different positions of the conduit controlling means.

Referring to the drawings in greater detail the numeral 1 designates a soda fountain of conventional type provided with a counter 2, syrup compartments 3 and supported upon a floor 4. Ordinarily the present type of soda fountains are provided with a plurality of faucets at the rear thereof adjacent the top which are hand operated by the soda fountain boy. These faucets are

often leaky and, of course, require one hand of the attendant in operating the same.

In lieu of such construction I have provided conduits for leading the carbonated water to the top of the soda fountain but controlled by the foot of the operator adjacent the bottom of the fountain. Specifically the construction comprises an outer conduit 5 and an inner conduit 6 which are 60 bent downwardly at their upper end as indicated by the numeral 7 in simulation of an ordinary faucet and to permit fluid to run into a glass held thereunder.

The outer conduit is bulged outwardly in 70 the form of a sphere 8 located just below the floor on which the fountain is supported and it is adjacent this bulged portion that the valve controlling mechanism and the means for operating the same are located.

The valve operating mechanism comprises 75 a cylinder 9 located on the interior of the conduit 5 and carrying a spider 10 which encircles the inner conduit 6. Attached to opposite sides of the cylinder 9 and operating 80 in slots 11 of the conduit 5 are pins 12 to which a foot operated lever 13 is pivoted. This lever 13 is normally held in raised position by means of spring 13'. Interposed 85 between the cylinder 9 and the walls of the outer conduit 5 are plates 9' which are of sufficient length to cover the slots 11 irrespective of the longitudinal position of the cylinder 9 within the conduit, and thereby 90 serving to prevent leakage through these 95 slots.

Rigidly connected with the cylinder 9 by means of legs 14 is a valve disc 15 which is adapted to cooperate with a valve seat 16 formed at the lower end of the outer conduit 95 5. This disc valve 15, of course, operates when in its closed position to shut off the passage of fluid through the conduit 5, and centrally fixed on this disc is a plug valve 17 which fits within the inner conduit 6 and 100 when in either of the positions shown in Figures 3 and 5 closes off the passage of fluid through this conduit. When the disc valve 15 is moved downwardly to rest upon its lower support 18, however, the plug 17 is entirely withdrawn from the inner conduit 6 and permits the passage of fluid upwardly 105 through the conduit.

Also rigidly connected with the cylinder 9 is an annular valve member 19 providing 110 a central aperture 20 which will co-operate with the outwardly flared end of the bell

mouth 21 formed on the inner conduit 6. This annular valve member when at its extreme upper limit as shown in Figure 3 or at an intermediate position as shown in Figure 5 will permit the passage of fluid past the outer wall of the inner conduit 6; but when in its lower position as shown in Figure 6 its engagement with the bell mouth 21 will shut off the passage of fluid through the central opening 20 and around the exterior of the conduit 6, but will in no way interfere with the passage of fluid through the interior of the conduit 6 which is open in this position of the annular valve member due to the fact that the plug 17 is withdrawn therefrom.

While the operation of the valve mechanism has been described in connection with the description of the several parts it may nevertheless be well to briefly summarize this action. With the foot lever 13 in raised position caused by spring 13' the valve mechanism takes the position shown in Figure 3 with the disc 15 seated upon its seat 16, plug 17 located within the inner conduit 6 and the annular valve member 19 disposed above the bell mouth 21. If now, it is desired to discharge carbonated water into a glass in a relatively large stream the foot lever 13 is pressed downwardly a short distance so as to move the disc valve 15 away from its seat 16 as shown in Figure 5. This position of the valve 15 permits the water to pass around the edges of the disc, around the outside of the bell mouth 21, and through the opening 20 in the valve member 19 and upwardly to the faucet 7. If it is now desired to direct a fine jet of water into the glass the foot lever 13 is moved downwardly to its lower limit which carries the valve mechanism to the position shown in Figure 6 at which time the disc valve 15 rests upon its support 18, the plug valve 17 is withdrawn from the inner conduit 6, and the annular valve member 19 seats on the bell mouth 21. The plug 17 being withdrawn from the conduit 6 and the annular valve member 19 being seated upon the bell mouth 21 the carbonated water is allowed to pass upwardly through the conduit 6, but is prevented from passing into the conduit 5 and therefore allows a fine jet of water to be projected into the glass held beneath the curved upper end 7 of the pipes. When the foot lever 13 is released, of course, the spring 13' will raise the same to its upper limit thereby bringing the valve mechanism to a position shown in Figure 3 and closing off entrance to both the outer and inner conduits 5 and 6.

From the foregoing description taken in connection with the accompanying drawings it will be apparent that I have devised a liquid dispensing device especially adapted for soda fountains which may be operated by the foot of the soda fountain attendant,

thereby leaving both hands free to manipulate glasses and the like; that is formed of relatively few parts; that does not involve the use of leather washers, gaskets and the like, and is therefore proof against wear such as encountered in ordinary soda fountain valves; and which is entirely leak-proof.

In accordance with the patent statutes I have described what I now believe to be the best embodiment of the invention; but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a liquid dispensing device including inner and outer conduits, rigidly connected valve elements for controlling either or both of said conduits.
2. In a liquid dispensing device including inner and outer conduits, a disc valve for closing the outer conduit, and a plug disposed on said disc valve and adapted to close said inner conduit.
3. In a liquid dispensing device including inner and outer conduits, a disc valve mounted for reciprocation and adapted to control said outer conduit, and a plug centrally fixed to said disc valve and adapted to control said inner conduit.
4. In a liquid dispensing device including inner and outer conduits, a plug for controlling said inner conduit, a disc valve for closing said outer conduit when the inner conduit is closed, and an annular valve member for closing said outer conduit when the inner conduit is opened.
5. In a liquid dispensing device including inner and outer conduits, a plug for controlling said inner conduit and valve elements associated therewith, one of which is adapted to close the outer conduit when the inner conduit is closed, and the other of which is adapted to close the outer conduit when the inner conduit is opened.
6. In a liquid dispensing device including inner and outer conduits, three rigidly connected valve elements comprising a plug, a disc, and a centrally perforated disc, said valve elements mounted for reciprocation and adapted to control the flow of liquid through said inner and outer conduits.
7. In a liquid dispensing device including inner and outer conduits, a bell mouth formed on the end of the inner conduit, an annular valve member disposed around said inner conduit and adapted to seat on the outer wall of said bell mouth, and a plug rigidly connected with said annular valve member and adapted to control the flow of fluid through said inner conduit.
8. In a liquid dispensing device including

inner and outer conduits, a bell mouth formed on the end of the inner conduit, a seat formed on the adjacent end of the outer conduit, a disc valve cooperating with said seat, a centrally fixed plug on said disc for closing said inner conduit, and an annular valve member spaced from said disc valve and encircling said inner conduit, said annular valve member being fixedly connected 10 to said disc valve and adapted to seat on the outer wall of said bell mouth.

9. In a liquid dispensing device including inner and outer conduits, a cylinder slidably mounted within the outer conduit and enclosing 15 the inner conduit, valve means mounted on said cylinder for controlling the flow of liquid through said conduits, said outer conduit provided with longitudinally extending slots, means extending 20 through said slots and engaging said cylinder for operating said conduit controlling

means, and plates disposed between said cylinder and the inner wall of said outer conduit for closing said slots.

10. In a liquid dispensing device including two conduits, valves for each of said conduits, and means for operating the valves, the construction and arrangement of the valves being such as to permit the closing of both conduits simultaneously or the 25 closing of either conduit while the other remains open.

11. In a liquid dispensing device including two conduits, rigidly connected valve elements for each of said conduits, and means 30 for operating the valve elements, the construction and arrangement being such as to permit the closing of both conduits simultaneously or the closing of either conduit while the other remains open.

OTIS SASSER.
